UNITED STATES PATENT OFFICE.

ALBION K. SPAULDING AND ALPHEUS M. SPAULDING, OF BELGRADE, AS
SIGNORS TO THE AUGUSTA WRENCH COMPANY, OF AUGUSTA, ME.

NUT-WRENCH.

SPECIFICATION forming part of Letters Patent No. 357,869, dated February 15, 1887.

Application filed July 14, 1886. Serial No. 207,990. (No model.)

To all whom it may concern:

Be it known that we, ALBION K. SPAULDING and ALPHEUS M. SPAULDING, citizens of the United States, residing at Belgrade, in the county of Kennebec and State of Maine, have invented certain new and useful Improvements in Wrenches; and we do hereby declare the following to be a full, clear, and exact description of the invention, such as will enable others skilled in the art to which it appertains to make and use same.

Our invention relates to that class of wrenches wherein the jaws are operated by the turning of the handle of the wrench; and the object of our invention is to make a wrench of this class which shall be simple and durable, and easily constructed.

The essential features of our wrench are a central core or spindle having at one end a fixed jaw, and having also a longitudinal slot within which is a flat bar secured to a sliding jaw, said bar having cut on its edges a screw-thread which engages a similar thread cut in a hollow metal handle.

We illustrate our invention by means of the accompanying drawings, in which Figure 1 shows a side view part in section. Fig. 2 shows a plan or top view. Fig. 3 is a view of central spindle. Fig. 4 is a view of flat screw, shown on a somewhat enlarged scale.

A is the central spindle or core, having formed at one end the fixed jaw A'. For something over half its length the spindle is of rectangular cross-section, the remaining distance, A², being round. At the extreme end is a portion of smaller diameter with a screw-thread cut on it. A slot, a, extending quite through the spindle, reaches for a considerable distance along the length of the same, this slot being sufficiently wide to receive the flat bar C, having screw-threads c c cut on its edges.

B is a movable jaw, so formed as to slide on the rectangular part of the spindle A. This

sliding jaw B is secured to the end of the screw C by a pin, b'.

D is a hollow metal handle, having at one end screw-threads d cut on its interior surface, and at the other end a shoulder, d', which, coming in contact with a shoulder, a'', formed on the spindle A, prevents it from moving 50 toward the jaws. The screw-threads d are made to engage the threads c on the edge of the screw C.

G is a nut, which screws on the end of spindle A and forms the tip of the handle.

The operation of our wrench is evident from its construction. The handle D is held in its place on the spindle by means of the shoulder a'' and the nut G. Upon being turned the screw threads d, engaging the screw-threads 60 c c on the bar C, move said bar back and forth, and with it the jaw B, to which it is attached. The handle D may be held in place on the spindle A by other means than the nut G and shoulder a''—as, for instance, by a pin playing 65 in a slot extending around the circular portion of spindle A, so that we do not wish to confine ourselves to the means here shown.

We claim—

A wrench composed of a central spindle with 70 a fixed jaw and a longitudinal slot, a sliding jaw adapted to move on said spindle and secured to a flat bar sliding in said slot and having cut on its edges screw-threads, which threads engage similar threads on the interior 75 surface of a hollow handle, said handle being provided with means for securing and holding it in position on the spindle, all as and for the purpose set forth.

In testimony whereof we affix our signatures 80 in presence of two witnesses.

ALBION K. SPAULDING.

ALPHEUS M. SPAULDING.
